OVER-MODULATION ALARM DEVICE

Orville E. Dow, Port Jefferson, N. Y., assignor to
 Radio Corporation of America, a corporation of
 Delaware

Application November 30, 1937, Serial No. 177,272

6 Claims. (Cl. 179—171.5)

My present invention relates to over-voltage and over-modulation alarm devices.

An object of the present invention is to provide an over-modulation alarm which is substantially independent of the variations in power supply line voltage. Another object of my invention is to provide an over-modulation alarm which is self-adjusting for small variations in carrier signal input. Still another object of my invention is to improve generally the accuracy and efficiency of over-modulation alarm devices.

Briefly, my present invention involves a pentode amplifier for the alternating current component of the rectified carrier. The plate current of a pentode tube is substantially independent of the plate voltage applied thereto within reasonable limits when the potential on the screens is maintained constant at the proper operating point. The screen grid voltage of the amplifier is maintained constant by means of a voltage regulator tube. Furthermore, in order to make the amplifier self-adjusting for varying carrier amplitudes the D. C. component of the rectified signal may be used to control the pentode plate current. A battery is used to supply normal grid bias to the amplifier when the signal level is normal.

For a given percentage modulation of the signal, the alternating current component of the rectified signal will increase proportionately to the increase in the direct current component. Therefore, since an increase in the carrier amplitude causes an increase in the plate current of the amplifier any increase in the carrier amplitude will require a correspondingly larger increase in the alternating current component to actuate the alarm.

Referring now to the drawing for a more complete description of my present invention, Fig. 1 shows a circuit diagram of one form of my invention while Fig. 2 shows a modification which provides for a compensation for varying carrier amplitudes. In Fig. 1, 10 and 12 represent the input to the device to which the rectified modulated carrier is supplied. In the following explanation the different electrode voltages referred to are taken with respect to the cathode of the tube. The alternating current component of the signal is applied to the grid of amplifier 21 through condenser 18. Tube 21 is a pentode amplifier tube and one of the characteristics of this type of tube is that the plate current is substantially independent of the plate voltage within reasonable limits. The plate voltage of tube 21 is supplied from rectifier 26 which is connected to

the alternating current supply line. The screen voltage for tube 21 is also supplied by the rectifier 26 through resistance 20. The glow-discharge tube 30 connected to the screen of tube 21 maintains the screen voltage substantially constant in spite of variations in the D. C. supply voltage.

The amplified alternating current component of the signal appears in potentiometer 23 and is applied through condenser 27 to the grid of glow-discharge tube 22. The plate voltage for the glow-discharge tube 22 is supplied by transformer 25. The grid bias of tube 22 is determined by the settings of potentiometers 24 and 23 and by the direct current through these potentiometers.

For a condition of zero signal input, i. e., with no modulation on the carrier, the slider of potentiometer 23 is placed at point A. The slider of potentiometer 24 is then adjusted until tube 22 is just on the point of conducting. The A. C. line voltage may be considered normal at this time. The maximum plate voltage E_b of tube 22 is the peak voltage appearing across the secondary of transformer 25. The direct current bias of this tube is the voltage between the slider and point D of potentiometer 24 and is just sufficient to prevent the tube from conducting. There is no A. C. voltage on the grid. Now, if the A. C. line voltage increases or decreases 10 per cent the plate voltage of tube 22 will increase or decrease 10 percent. Also, the bias will correspondingly increase or decrease 10 percent and the tube is still operating at the point of break-down, that is, any amplitude of the alternating current component of the rectified carrier applied across the input 10, 12 will cause the tube to conduct and actuate relay 32 to operate the alarm.

For a condition of fixed signal input other than zero, the potentiometer 24 is left as adjusted for the zero signal condition. The slider of potentiometer 23 is moved toward point B until the tube 22 just fails to conduct. The maximum plate voltage E_b of 22 is, as before, the peak voltage across the transformer 25. The bias voltage impressed on the grid is the voltage E_1 between the slider and point D of potentiometer 24, plus the voltage E_2 between the point A and the slider of potentiometer 23 due to the plate current of tube 21. The A. C. voltage on the grid of tube 22 is the A. C. component of the signal amplified by tube 21 and appearing across the whole of potentiometer 23. The peak value of this voltage E_{ac} is equal to the D. C. voltage E_2 between point A and the slider of potentiometer 23. Therefore, the minimum instantaneous bias of tube 22 is equal to the voltage E_1 between the slider and

point D of potentiometer 24. From the condition of zero signal it has been shown that the voltage E_1 and the plate voltage of tube 22 maintain the proper relation to each other, as the line voltage is varied, to keep the tube 22 at the proper operating point. Now, if the peak alternating current voltage E_{ac} across the potentiometer 23 and the D. C. voltage E_2 between the point A and the slider potentiometer 23 remain equal, the device is independent of line voltage. The A. C. voltage E_{ac} will be independent of line voltage so far as the amplification of tube 21 is independent of plate voltage. It has already been shown that the direct current in potentiometer 23 is independent of line voltage within reasonable limits and, therefore, E_2 is independent of the line voltage within the same limits. Actual measurements show that the accuracy is decreased by only 1 percent when the line voltage changes by plus or minus 15 percent.

For the device of Fig. 1 to operate accurately as an over-modulation alarm the direct current component of the signal input must be kept at a predetermined value. In the prior art, as far as I am aware, this is usually done manually. The voltage on the radio frequency transmission line of a short wave or ultra-short wave transmitter varies with the weather conditions. Hence, the rectified input to the monitor will vary and will require the input to be readjusted to its proper value. Fig. 2 shows a modification of the input circuit of Fig. 1 that makes it self-adjusting for small variations in carrier signal input. The battery 29 is provided which balances out the normal direct current component of the signal and also supplies normal bias to tube 21. If the carrier arises above normal values the plate current of tube 21 increases correspondingly. This increases the bias on tube 22. For the same percentage modulation of the signal the increase in the alternating current component of the signal is proportional to the increase of the direct current component. Thus, the A. C. voltage across potentiometer 23 increases by the same amount that the bias on tube 22 was increased and the circuit remains in its predetermined condition of sensitivity within reasonable limits.

A decrease in the plate current of tube 21 decreases the voltage drop through resistor 23. The potential E_2 therefore becomes smaller and the potential on the slider on resistor 23 thus becomes more positive since the total voltage drop from point D to point B is substantial proportional to the conductivity of the tube 21. It will thus be seen that as the plate current of tube 21 decreases the value of E_2 decreases and the grid of tube 22 is rendered less negative. The negative bias on the grid of tube 22 due to the current flow through potentiometer 24 from source 26 is substantially fixed and is of itself insufficient to prevent conduction of tube 22. Therefore, when E_2 decreases sufficiently the grid of tube 22 is rendered sufficiently less negative that the tube becomes conductive and the alarm is thus energized.

In the above description the tube 22 was supplied with A. C. voltage on its plate. The purpose of this is to return control to the grid when the discharge is extinguished on the negative half of the cycle. The tube 22 may be supplied with plate voltage from rectifier 26 if it is desired to have the alarm continue to operate until it is reset by opening the plate circuit. The operation of the device will not be changed.

75 While I have indicated and described a par-

ticular arrangement for carrying my invention into effect, my invention is by no means limited to the particular organization shown and described and modifications may be made without departing from the scope and spirit of the invention.

I claim:

1. An over-modulation alarm device comprising an input circuit for a rectified modulated signal; means for separating the alternating current component from said signal; amplifying means for said alternating current component, said means comprising a pentode tube having a plate and a screen grid, a constant source of potential connected to said screen grid, 10 a source of potential for said plate, a resistance connected between said plate and said source of potential, a grid controlled gas discharge tube having a grid and a plate means for normally biasing said grid controlled gas discharge tube 15 inoperative and means responsive to a decrease in the plate current of said pentode below a predetermined value for removing said bias and an alarm circuit connected to the plate of said grid controlled gas discharge tube. 20

2. A device of the character described comprising an input circuit for a rectified modulated carrier having a direct current and an alternating current component, an amplifier including a pentode tube having a control grid, a screen 30 grid and a plate, a source of potential for biasing said control grid and for opposing the normal direct current component of said carrier, a grid controlled gas discharge tube having grid and plate circuits, an alarm in the plate circuit 35 of said gas discharge tube, a source of potential connected to the plates of said gas discharge and said pentode tubes, said source being subject to voltage fluctuations, means for applying a constant potential to the screen of said pentode tube 40 whereby the plate current of said tube is substantially unaffected by voltage fluctuations in said source; means for biasing said gas discharge tube inoperative and means for connecting said gas discharge tube grid circuit to the pentode tube so that a change in the direct current component of the rectified signal produces a proportional change in said bias whereby the alarm in the plate circuit of said gas discharge tube is operated. 45

3. An over-modulation alarm device comprising an input circuit for a rectified modulated signal, means for separating the alternating current component from said signal, amplifying means for said alternating current component, 50 said means including a pentode tube having a plate and a screen grid, a grid controlled gas discharge tube having grid and plate circuits, means for normally biasing said grid controlled gas discharge tube inoperative, an alarm in the 55 plate circuit of said gas discharge tube, means for so connecting the grid circuit of said gas discharge tube to the plate of said pentode tube that a decrease in the plate current of said pentode below a predetermined value removes said bias and actuates said alarm, a power supply line subject to voltage fluctuations, means for energizing the plate circuit of said gas discharge tube from said line, means energized from said line for supplying a direct potential to the plate 60 of said pentode and to said biasing means and means including a second gas discharge tube for supplying a constant voltage to the screen grid of said pentode. 65

4. An over-modulation alarm device compris-

- ing an input circuit for a rectified modulated signal, means for separating the alternating current component from said signal, amplifying means for said alternating current component, said means including a pentode tube having a plate and a screen grid, a grid controlled gas discharge tube having grid and plate circuits, means for normally biasing said grid controlled gas discharge tube inoperative, an alarm in the 5 plate circuit of said gas discharge tube, means for so connecting the grid circuit of said gas discharge tube to the plate of said pentode tube that a decrease in the plate current of said pentode below a predetermined value removes said 10 bias and actuates said alarm, an alternating current power supply line subject to voltage fluctuations, means for energizing the plate circuit of said gas discharge tube from said line, a rectifier connected to said line for supplying a direct potential to the plate of said pentode and to said biasing means and means including a second gas discharge tube for supplying a constant voltage to the screen grid of said pentode. 15
5. An over-modulation alarm device comprising an input circuit for a rectified modulated signal, means for separating the alternating current component from said signal, a pentode tube having a control grid connected to said means, a cathode, a screen grid and a plate; a grid controlled gas discharge tube having a grid and a plate, a condenser connected from the plate of said pentode to the grid of said gas discharge tube, an alternating current power line subject to voltage fluctuations, means for energizing the 20 plate of said gas discharge tube from said line, an alarm connected between said plate and said means, a rectifier having its input terminals connected to said line and a voltage divider connected to its output, a connection including a series resistance from the plate of said pentode to an intermediate point on said voltage divider, a resistance connected from the grid of said gas discharge tube to a tap on said plate resistance, a connection from the cathode of said gas discharge tube to a point on said voltage divider 25
- more positive than said intermediate point whereby said gas discharge tube is normally biased inoperative, a second gas discharge tube and a resistance connected in series across said voltage divider, and a connection from the screen grid of said pentode tube to the junction between said last resistance and said second gas discharge tube whereby a substantially constant potential is applied to said screen grid. 30
6. An over-modulation alarm device comprising an input circuit for a rectified modulated signal, means for separating the alternating current component from said signal, a pentode tube having a control grid connected to said means, a cathode, a screen grid and a plate; a grid controlled gas discharge tube having a grid and a plate, a condenser connected from the plate of said pentode to the grid of said gas discharge tube, an alternating current power line subject to voltage fluctuations, means for energizing the 35 plate of said gas discharge tube from said line, an alarm connected between said plate and said means, a rectifier having its input terminals connected to said line and a voltage divider connected to its output, a connection from the cathode of said gas discharge tube to a point on said voltage divider more positive than said intermediate point whereby said gas discharge tube is normally biased inoperative, a second gas discharge tube and a resistance connected in series across said voltage divider, and a connection from the screen grid of said pentode tube to the junction between said last resistance and said second gas discharge tube whereby a substantially constant potential is applied to said screen grid. 40
